FLOW RESTRICTING DEVICE

Franklyn Young Carter, Dearborn, Mich., assignor to Detroit Lubricator Company, Detroit, Mich., a corporation of Michigan

Application August 9, 1946, Serial No. 689,620

4 Claims. (Cl. 138—42)

1

This invention relates to a device for restricting the flow of refrigerant to an evaporator.

An object of the invention is to provide a device of novel construction which can be readily manufactured at low cost.

Another object is to provide such a device in which a filter of large capacity can be incorporated.

The invention consists in the novel construction and combination of parts to be more fully described hereinafter and the novelty of which will be particularly pointed out and distinctly claimed.

In the accompanying drawings, to be taken as a part of this specification, there is fully and clearly illustrated a preferred embodiment of the invention, in which drawings:

Figure 1 is an end view of the flow restricting device;

Fig. 2 is an enlarged view in section on the line 2—2 of Fig. 1;

Fig. 3 is a view in section on the line 3—3 of Fig. 2;

Fig. 4 is a view on the same scale as Fig. 1 and in longitudinal section on the line 4—4 of Fig. 2, and

Fig. 5 is a detail view of an end plate in section, showing a modification.

Referring to the drawings by characters of reference, 1 designates a hollow internally cylindrical casing forming a cylindrical chamber 2. The casing has an end wall 3 from which a tubular inlet fitting 4 projects concentrically and is externally screw-threaded for connection to the refrigerant liquid line from the receiver or condenser. The fitting bore or passageway 5 opens through the wall 3 into the chamber 2. Within the chamber 2 there is a hollow cylindrical flow restricting member 6 having its external surface serrated or fluted by alternate lands 7 and grooves 8 extending parallel and longitudinally from end to end of the member 6. The lands 7 have a tight sliding or press fit in the casing 1 so that the grooves 8 are sealed laterally from each other. Tightly clamped between and conforming to the end wall 3 and the end of the member 6, there is an end plate 9 having its periphery serrated or notched to provide recesses 10 separated by teeth 11. The radial depth of the notches or recesses 10 is less than the thickness of the member 6 but not less than that of the grooves 8. Each recess 10 has a circumferential width to span two of the grooves 8 so that each recess provides a return bend passageway between two adjacent grooves. The teeth 11

2

align with alternate lands 7 and are of substantially equal width therewith. Through the plate 9 there is a central aperture 12 registering with the passageway 5. Radially through the member 6, there is a port or aperture 13 which opens into the inlet groove 14 of the grooves 8.

The other end of the casing 1 is closed by an end wall 15 in the form of a circular plate which is sealed to the casing. The plate 15 has a centrally positioned outlet fitting 16 which is externally screw-threaded to receive a conduit leading to an evaporator or refrigerating coil. The bore 17 of the fitting 16 opens through the wall or plate 15. Clamped between and conforming to the opposed faces of the plate 15 and the adjacent end of the member 6 there is an end plate 18 having its periphery serrated or notched to provide recesses 19 separated by teeth 20. The plate 18 is generally similar to the plate 9, except that one tooth 21 has a width to bridge the lands 7 at the sides of the groove 14 and thus block off the lower end of the groove 14. The next adjacent groove 22 of the grooves 8, to the right of the inlet groove 14 facing Fig. 2, is in communication with the groove 14 at its upper end through a return bend passageway 10. The teeth 20 are staggered or aligned with alternate ones of the lands 7 relative to the alignment therewith of the teeth 11, so that the return bend passageways 10 or recesses 19 and 19 are a continuous zig-zag or sinuous flow restricting passageway having as its last pass or run, the groove 23 of the grooves 8, i. e. the groove next adjacent but on the left, facing Fig. 2, of the groove 14. The space or notch between the tooth 21 and the next adjacent tooth to the left thereof, provides an outflow recess which communicates with a radial groove or passageway 24 in the end wall 15. The inner end of the passageway 24 opens into the outlet fitting bore 17. The member 6 and the end plates 9 and 18 are preferably made of extruded metal stock and may have the end faces of the lands and teeth ground to assure a leak proof fit with the internal surface of the casing 1 which may also be a ground surface. The end plates 9 and 18 can be made from the same stock piece and thereafter have the tooth 21 formed in part by an insert 25, see Fig. 5. The space or chamber 26 within the member 6 and between the plates 9 and 18 serves as a strainer or filter chamber. Clamped between the plates 18 and the adjacent end of the member 6 there is a strainer supporting ring carrying a cup-like strainer 27 of fine wire mesh with its end wall adjacent the inlet passageway 5. The strainer cup is filled with filter-

ing material 28 so that no foreign matter which might clog the grooves 8 can gain access thereto.

The operation of the flow restricting device, it having been connected in a refrigerant liquid line to an evaporator, is as follows: The liquid refrigerant enters the strainer chamber through the inlet passageway 5 and is filtered therein prior to discharge through the port 13. The refrigerant then flows through the elongated sinuous passageway formed by the grooves 8 of small cross-sectional flow area thereby limiting or restricting the flow to a predetermined amount or rate in the same manner as the well known so-called capillary tube. The restricted flow discharges through the radial groove 24 into the outlet fitting bore 17 and thence to the evaporator.

Having thus described my invention, what is claimed and is desired to be secured by Letters Patent of the United States is:

1. A refrigerant flow restricting device, comprising a casing having a cylindrical chamber and end closure walls for said chamber, one of said walls having an inlet therethrough, the other of said walls having an outlet therethrough, a hollow cylindrical member having a tight sliding fit in said chamber and having straight longitudinal alternate lands and grooves from end to end in its external surface, a pair of end plates each abutting one of said end walls and said cylindrical member and one having an opening therethrough registering with said inlet, said end plates each having a tight sliding fit in said chamber and having peripheral teeth and serrations of less radial depth than the wall thickness of said cylindrical member, each of said serrations having a circumferential width to register with two of said grooves so that each serration forms a return bend passageway joining two adjacent grooves, said cylindrical member having a port which opens from the interior thereof into one of said grooves, one of the teeth of the other of said end plates having a width to block off the end of said one groove into which said port opens, the next adjacent groove which is separated from said one groove by a tooth of said one end plate being the outlet groove, said other end plate having its teeth alined with alternate ones of the lands with which the teeth of said one plate aline, the serration in said other plate which is alined with said outlet groove having communication with said outlet.

2. A refrigerant flow restricting device, comprising a casing having a cylindrical chamber and end closure walls for said chamber, one of said walls having an inlet therethrough, the other of said walls having an outlet therethrough, a hollow cylindrical member having a tight sliding fit in said chamber and having straight longitudinal alternate lands and grooves from end to end in its external surface, a pair of end plates each abutting one of said end walls and said cylindrical member and one having an opening therethrough registering with said inlet, said end plates each having a tight sliding fit in said chamber and having peripheral teeth and serrations of less radial depth than the wall thickness of said cylindrical member, each of said serrations having a circumferential width to register with two of said grooves so that each serration forms a return bend passageway joining two adjacent grooves, said cylindrical member having a port which opens from the interior thereof into one of said grooves, one of the teeth of the other of said end plates having a width to block off the end of said one groove into which said port opens, the next adjacent groove which is separated from said one groove by a tooth of said one end plate being the outlet groove, said other end plate having its teeth alined with alternate ones of the lands with which the teeth of said one plate

to block off the end of said one groove into which said port opens, the next adjacent groove which is separated from said one groove by a tooth of said one end plate being the outlet groove, said other end plate having its teeth alined with alternate ones of the lands with which the teeth of said one plate aline, one of the abutting surfaces between said cylindrical member and said other plate having a radial groove leading to said outlet from the serration in said other plate which is alined with said outlet groove.

3. A refrigerant flow restricting device, comprising a casing having a cylindrical chamber and end closure walls for said chamber, one of said walls having an inlet therethrough, the other of said walls having an outlet therethrough, a hollow cylindrical member having a tight sliding fit in said chamber and having straight longitudinal alternate lands and grooves from end to end in its external surface, a pair of end plates each abutting one of said end walls and said cylindrical member and one having an opening therethrough registering with said inlet, said end plates each having a tight sliding fit in said chamber and having peripheral teeth and serrations of less radial depth than the wall thickness of said cylindrical member, each of said serrations having a circumferential width to register with two of said grooves so that each serration forms a return bend passageway joining two adjacent grooves, said cylindrical member having a port which opens from the interior thereof into one of said grooves, one of the teeth of the other of said end plates having a width to block off the end of said one groove into which said port opens, the next adjacent groove which is separated from said one groove by a tooth of said one end plate being the outlet groove, said other end plate having its teeth alined with alternate ones of the lands with which the teeth of said one plate aline, one of the abutting surfaces between said cylindrical member and said other plate having a radial groove leading to said outlet from the serration in said other plate which is alined with said outlet groove, and strainer means in said cylindrical member.

4. A refrigerant flow restricting device, comprising a casing having a cylindrical chamber and end closure walls for said chamber, one of said walls having an inlet therethrough, the other of said walls having an outlet therethrough, a hollow cylindrical member having a tight sliding fit in said chamber and having straight longitudinal alternate lands and grooves from end to end in its external surface, a pair of end plates each abutting one of said end walls and said cylindrical member and one having an opening therethrough registering with said inlet, said end plates each having a tight sliding fit in said chamber and having peripheral teeth and serrations of less radial depth than the wall thickness of said cylindrical member, each of said serrations having a circumferential width to register with two of said grooves so that each serration forms a return bend passageway joining two adjacent grooves, said cylindrical member having a port which opens from the interior thereof into one of said grooves, one of the teeth of the other of said end plates having a width to block off the end of said one groove into which said port opens, the next adjacent groove which is separated from said one groove by a tooth of said one end plate being the outlet groove, said other end plate having its teeth alined with alternate ones of the lands with which the teeth of said one plate

aline, one of the abutting surfaces between said cylindrical member and said other plate having a radial groove leading to said outlet from the serration in said other plate which is alined with said outlet groove and a cup-like strainer in said cylindrical member and having a supporting ring clamped between said other plate and said cylindrical member.
